LINE CASTING SLUG LENGTH CONTROL

Leon Kraft and Clark H. Thompson,
San Diego, Calif.

Application December 26, 1930, Serial No. 504,794

14 Claims. (Cl. 199—55)

Our invention relates to line casting slug length controls, and the objects of our invention are:

First, to provide a device of this class which is particularly adapted for use in connection with 5 machines which cast the large sizes of type, such as type used for headlines;

Second, to provide a device of this class which may be installed on the line casting machine with but superficial changes in the construction of the 10 machine;

Third, to provide a device of this class which adjusts the slug casting portions of a type setting machine, so as to cast a slug equal to the length of the various rows of type characters 15 formed by the machine;

Fourth, to provide a device of this class which eliminates the labor and waste material occasioned by sawing off excess lengths of the slugs;

Fifth, to provide a device of this class which 20 eliminates the overhanging of the type beyond the end of the slugs and the consequent danger of the type breaking down;

Sixth, to provide a device of this class which permits a snug fit between the slug casting molds 25 and the slug length control bar, so as to prevent the formation of projecting fringes;

Seventh, to provide a device of this class in which the various lengths of slugs cast thereby have exact dimensions;

Eighth, to provide a device of this class which 30 in no manner damages or hinders the operation of the slug casting mold, in particular, does not mutilate or wear the corners bordering the face end of the slug casting slot, thus insuring forming of sharp corners between the type casting 35 and the slugs;

Ninth, to provide a device of this class which, should obstructions prevent the proper operation thereof, the device will not jam or injure the line 40 casting machine, the device merely causing the casting of a slug of improper length, thus only requiring the re-casting of the line of type or the removal of the excess length of slug;

Tenth, to provide a device of this class which 45 makes only a minimum change in the operation of the machine to which it is attached; and

Eleventh, to provide on the whole a novelly 50 constructed line casting slug length control which is particularly simple of construction and of operation, durable, efficient in its action, and which will not readily deteriorate or get out of order.

With these and other objects in view as will appear hereinafter, our invention consists of certain novel features of construction, combination, 55 and arrangement of parts and portions as will

be hereinafter described in detail and particularly set forth in the appended claims, reference being had to the accompanying drawings and to the characters of reference thereon, which form a part of this application, in which:

Figure 1 is a plan view of our control with parts and portions broken away and in section, showing also a limited portion of the machine to which the control is attached; Fig. 2 is an enlarged fragmentary sectional view through 2—2 of Fig. 1; Fig. 3 is another enlarged fragmentary sectional view through 3—3 of Fig. 1, with parts and portions as shown in elevation; Fig. 4 is an enlarged bottom view of the slug length control bar, its guide, stop mechanism and operating 70 arm, and showing adjacent portions of the table top and slug casting mold fragmentarily; Fig. 5 is an enlarged fragmentary sectional view through 5—5 of Fig. 1, with parts and portions shown in elevation; and Fig. 6 is a fragmentary 75 sectional view through 6—6 of Fig. 4, showing the slug casting mold and the adjacent end of the slug length control bar; and Fig. 7 is a diagrammatical developed view of the cam portions 80 illustrated in Fig. 5.

Similar characters of reference refer to similar parts and portions throughout the several views of the drawings.

Slug casting mold 1, slug length control bar 2, guide member 3, guide keeper members 4, shank 85 5, stop member 6, scale plate 7, movable grip 8, lug 9, lever member 10, supporting plate 11, segmental gear 12, sleeve member 13, bearing 14, shaft 15, bearing 16, spring 17, lever 18, link 19, and bracket 20 constitute the principal parts 90 and portions of our line casting slug length control.

The line casting mold 1 is conventional except that the slot designated 1a extends to the forward extremity of the mold and the corners 1b thereof at this extremity are rounded, as shown in Figs. 1 and 4. In order to reinforce this end and prevent spreading of the slot, and further to enable the formation of a water cooling passage, there is provided a web 1c, which bridges the slot at the under side of the slug casting mold adjacent the forward end thereof, as shown in Fig. 4.

The slug casting mold shifts in a vertical plane. 105 When in its upper position, the slug casting mold registers with and extends part way into an opening T1 provided in the table T. While the mold is in its upper position, the slug and type are cast, while the mold is in its lower posi- 110

tion, the newly formed slug and type are removed.

It will be noted that the table T is of the conventional hinged type.

5 The slug length control bar 2 is slidably mounted adjacent the under side of the table top T and extends forwardly from the opening T1 therein. The portion of the control bar adjacent its extremity is increased in height, as indicated by 2a, so as to project into the opening T1 and terminate flush with the upper face of the mold, as shown in Fig. 6. When the control bar is in its forward position, the upwardly projecting portion 2a is adjacent the forward margin of the opening T1. The lower surface of the control bar 2 is smooth, and is adapted to close the outlet holes of a casting mouthpiece P1 of a type metal casting pot P, which would otherwise cast the excess length of slug. Forwardly from the projection 2a, the bar clears the under side of the table T.

At its forward lower portion the bar 2 is provided with a laterally extending web 2b. The web 2b is connected preferably integrally with a guide member 3 which extends in parallel disposed relation with the slug length control bar 2 and in offset relation to the slot T1 of the table top.

30 The guide member 3 is substantially rectangular in cross section, and is provided with ridges 3a along its side margin. These ridges 3a are adapted to be slidably mounted in channels 4a of guide keeper members 4. The guide keeper members 4 are secured to the under side of the table top, as shown best in Figs. 1, 2, 3, and 4.

One of the guide keeper members, preferably the one remote from the control bar 2, in addition to functioning as a guide keeper member, forms a base for a shaft mechanism. This base 40 portion, designated 4b, is arranged toward the forward portion of the keeper member along the side thereof. Formed in the base portion 4b is a slot 4c arranged in parallel disposed relation with the line of travel of the control bar. 45 Bordering the slot 4c along the under face of the base 4b, there is formed a rack 4d.

The slot 4c is adapted to receive a shank 5, to the lower end of which is attached a stop member 6. The upper face of the stop member 50 6 is provided with teeth 6a which are adapted to fit in the teeth of a section of the rack 4d, as shown in Figs. 3 and 4.

The upper end of the shank 5 is provided with a fixed grip 5a having a pointer 5b extending laterally therefrom adjacent the top of the table. The pointer 5b is adapted to register with a scale plate 7, which is affixed to the top of the table T, as shown best in Figs. 1, 2, and 3.

Supported at the upper end of the shank 5 60 is a movable grip 8, which is in the form of a cam lever with an arm portion 8a arranged opposite the fixed grip 5a. Between the two grips there is provided a spring 8b, which tends to force the grips apart, and by so doing holds the teeth of the stop 6 in engagement with the rack. Shifting of the movable grip 8 towards the fixed grip 5a, permits slight downward shifting of the shank 5 and disengagement of the teeth 6a with the rack so that the stop may be shifted therealong to the desired position. The markings of the scale correspond to the teeth of the rack so that the stop may be positioned accurately.

Arranged on the under side of the guide member 3, adjacent its forward end, is a depending lug 9, which is adapted to be engaged by the

forked extended end 10a of a lever member 10. The lever 10 is supported by the table top T and extends sidewise adjacent the under side thereof and within the frame, designated F, which supports the table top. The lever 10 is rotatably mounted upon a stub shaft 11a which depends from a supporting plate 11 secured to the under side of the table top near the side margin of the frame F, as shown in Figs. 1 and 5. Also depending from the support 11 is a stub shaft 11b upon which is rotatably mounted a segmental gear 12. The teeth of the segmental gear 12 are adapted to engage a segmental gear portion, designated 10b, arranged at the opposite extremity of the lever 10 from the forked end 10a thereof. The lower surface of the segmental gear 12 is provided with an annular cam portion 12a, which is adapted to fit in a complementary cam portion 13a of a sleeve member 13. One cam portion is provided with a projection, while the other cam portion is provided with a corresponding depression, as shown in Fig. 5, and in the diagrammatical view, Fig. 7. Thus, the two cam portions are normally interlocked. However, the table top is free to be lifted from the frame F.

The sleeve member 13 is supported in a vertical position by a suitable bearing 14 attached to the frame in any suitable manner.

The sleeve 13 is slidably mounted upon a shaft 15, but is keyed against rotation relative thereto. The shaft 15 is journalled at its lower end portion in a bearing 16. Between the bearings 14 and 16, there is mounted a tension spring 17. This is supported at its end portion in spring retaining washers 17a. The lower end of the sleeve 110 member 13 is flush with the lower end of the bearing 14 and engages the uppermost washer 17a, so that downward movement of the sleeve member past the lower end of the bearing 14, compresses the spring 17, as shown in Fig. 5.

Attached to the lower end of the shaft 15, is a lever 18, which extends rearwardly within the frame F to a point opposite a cam shoe mechanism M, which supports the type metal containing pot and shifts it in the desired manner. 120 At this end, the lever 17 is connected by a link 18 to a bracket 19, which is fixed to the cam shoe mechanism M. This connection between the lever 18 and bracket 20 is such as to allow vertical movement of the mechanism M without causing 125 an appreciable rotation of the shaft 15. However, lateral movement of the cam shoe mechanism M on its cam C produces an arcuate movement for the extreme movement of the slug length 130 control bar 2.

Operation of our line casting slug length control is as follows:

The stop member 6 is set so that when it is engaged by the lever member 10, the length of 135 the slot between the extremity of the bar 2 and the fixed end of the slot 1a, is of the desired amount. When the type metal containing pot P is being shifted to the position for casting, the various levers and shafts connected with the slug 140 length control bar 2 shift the control bar inwardly until the stop 6 is engaged by the lever member 10. Further movement causes the sleeve 13 and cam portion 13a to shift relative to the cam portion 12a, compressing the spring 17. The 145 force of the spring transmitted through the cams and lever 10 is more than sufficient to hold the slug length control bar firmly in place during the casting operation.

The upward movement of the slug casting 150

mold 1 is in advance to the shifting of the type metal containing pot so that the mold is in its upper position against the matrix M before the slug length control bar begins to enter therein. 5 Thus, the control bar 2 is moved endwise with respect to the slot 1a and in no wise strikes the corners between the slot 1a and the upper face of the casting mold.

It will be noted that the movement of the control bar 2 is so turned as to both enter and withdraw from the mold, while the mold remains in its upper position.

It is preferred to have the extreme outer position of the control bar 2 as close to the end of the slot 1a as possible so that even though there should be no movement of the control bar due to an obstruction, there would be but a very small space between the control bar and the mold through which the molten type metal might 20 squirt, thus eliminating any danger of an accident. A further arrangement is accomplished by limiting the outward position of the stop member 6, so that even though it is not set, the length control bar will move in far enough to cast the maximum length of slug which the machine is 25 adapted to produce.

This arrangement has the further advantage that the setting of the machine for full size slugs, which are most often wanted, may be made merely by shifting the stop to its extreme position.

Though we have shown and described a particular construction, combination, and arrangement of parts and portions, we do not wish to be limited to this particular construction, combination and arrangement, but desire to include in the scope of our invention the construction, combination, and arrangement substantially as set forth in the appended claims.

Having thus described our invention, what we 40 claim as new and desire to secure by Letters Patent is:

1. In a line casting slug length control, a water cooled slug casting mold including a slot intersecting an end thereof, water passages bordering said slot, and an offset hollow web bridging the extremity of said slot and forming a portion of said water passages, a slug length control bar 45 slideable in said slot from the end of said mold, and means for shifting said bar into said slot a predetermined distance.

2. In a line casting slug length control for type casting machines, a horizontally disposed table including a mold receiving opening, a movable slug casting mold arranged to shift upwardly into said opening, said mold provided with a slug forming slot intersecting one end thereof, a slug length control bar slideable into said slot from the end of said slug casting mold, and shifting means timed relative to the movement of said slug casting mold whereby said slug length control bar is moved onto said slot when said mold is in position for casting.

3. In a line casting slug length control for type casting machines, a horizontally disposed table including a mold receiving opening, a movable slug casting mold arranged to shift upwardly into said opening, said mold provided with a slug forming slot intersecting one end thereof, a slug length control bar slideable into said slot from the end of said slug casting mold, shifting means timed relative to the movement of said slug casting mold whereby said slug length control bar is moved onto said slot when said mold is 70 in position for casting, and means for limiting

and controlling the movement of said slug length control bar into said slot.

4. In a line casting slug length control for type casting machines, a movable slug casting mold, including a slot intersecting an end thereof, water cooling means associated therewith and a hollow offset reinforcing web disposed at an extremity of said slot and forming a part of said water cooling means, a slug length control bar supported by the table top of said type casting machine arranged to enter said slot when said mold is in its casting position, and shifting means timed relative to the movement of said slug casting mold for shifting said bar.

5. In a line casting slug length control for type casting machines including a horizontally disposed table, a movable slug casting mold, said mold provided with a slot intersecting an end thereof, a slug length control bar supported from the under side of the table top of said type casting machine arranged to enter said slot when said mold is in its casting position, shifting means timed relative to the movement of said slug casting mold for shifting said bar, and set means operable from the upper side of said table top for regulating the depth of penetration of said bar in said slot.

6. In a line casting slug length control for type casting machines including a hinged horizontally disposed table top, a movable slug casting mold, said mold provided with a slot intersecting an end thereof, a slug length control bar supported by said table top arranged to enter said slot when said mold is in its casting position, shifting means timed relative to the movement of said slug casting mold for shifting said bar, a disconnectable and yieldable coupling means included in said shifting means arranged to disconnect upon raising of said table top, said coupling means yieldable to force in excess of 115 that required to shift said bar, whereby the driving side of said coupling means may continue its movement, and adjustable stop means for limiting the penetration of said bar into said slot.

7. The combination with a type casting machine including a table top, mechanism for causing vertical shifting of a slug casting mold to a position contiguous to the under side of said table top, and cam means for shifting a type 125 metal containing pot into registration with said slug casting mold, of a line casting slug length control, including a slug casting mold provided with a slot intersecting an end thereof, a slug length control bar supported from the underside 130 of said table top and slideable into said slot, and actuating means for said bar operated by said pot shifting cam means for moving said bar into said slot from the end of said mold when said mold is in its upper or casting position.

8. The combination with a type casting machine including a table top, mechanism for causing vertical shifting of a slug casting mold to a position contiguous to the under side of said table top, and cam means for shifting a type 140 metal containing pot into registration with said slug casting mold, of a line casting slug length control, including a slug casting mold provided with a slot intersecting an end thereof, a slug length control bar supported from the under side 145 of said table top and slideable into said slot, actuating means for said bar operated by said pot shifting cam means for moving said bar into said slot from the end of said mold when said mold is in its upper or casting position, and con- 150

trol means operable from the upper side of said table top for determining the amount of penetration of said bar into said slot.

9. The combination with a type casting machine including a table top, mechanism for causing vertical shifting of a slug casting mold to a position contiguous to the under side of said table top, and cam means for shifting a type metal containing pot into registration with said slug casting mold, of a line casting slug length control, including a slug casting mold provided with a slot intersecting an end thereof, a slug length control bar supported by said table top and slideable into said slot, actuating means for said bar operated by said pot shifting cam means for moving said bar into said slot from the end of said mold when said mold is in its upper or casting position, and a coupling included in said actuating means, said coupling being separable upon raising of said table top.

10. The combination with a type casting machine including a table top, mechanism for causing vertical shifting of a slug casting mold to a position contiguous to the under side of said table top, and cam means for shifting a type metal containing pot into registration with said slug casting mold, of a line casting slug length control, including a slug casting mold provided with a slot intersecting an end thereof, a slug length control bar supported by said table top and slideable into said slot, actuating means for said bar operated by said pot shifting cam means for moving said bar into said slot from the end of said mold when said mold is in its upper or casting position, and yieldable means included in said actuating means, said yieldable means arranged to yield to a force greater than that required for shifting said bar, and stop means for blocking the action of said actuating means and limiting the movement of said bar into said slot.

11. In a type casting machine wherein a line of matrices is positioned over an opening in a horizontally disposed table and a slug casting mold and type metal pot disposed under the table is shifted into registration with said opening and matrices, the combination with said slug casting mold of slug length control bar supported from the under side of said table independently

of said slug casting mold and slideable into the casting portion of said mold.

12. In a type casting machine wherein a line of matrices is positioned over an opening in a horizontally disposed table and a slug casting mold and type metal pot disposed under the table is shifted into registration with said opening and matrices, the combination with said slug casting mold of a slug length control bar supported from the under side of said table independently of said slug casting mold and slideable into the casting portion of said mold, and an operating means for said slug length control bar associated with the operating mechanism of said type casting machine, said operating means being disposed wholly below said table.

13. In a type casting machine wherein a line of matrices is positioned over an opening in a horizontally disposed table and a slug casting mold and type metal pot disposed under the table is shifted into registration with said opening and matrices, the combination with said slug casting mold of a slug length control bar supported from the under side of said table independently of said slug casting mold and slideable into the casting portion of said mold, an operating means for said slug length control bar associated with the operating mechanism of said type casting machine, said operating means being disposed wholly below said table, and stop means for limiting the movement of said slug length control bar operable from the upper side of said table.

14. In a type casting machine of the class wherein a line of matrices is positioned over an opening in a horizontally disposed table and first a slug casting mold, then a type metal pot both arranged below said table are shifted into registration with said opening and matrices, the provision in said mold of a slug casting slot intersecting an end thereof, and the combination with said slot of a slug length control bar slidably supported from the under side of said table and shiftable into said slot when said slug casting mold is in registration with said matrices.

LEON KRAFT.
CLARK H. THOMPSON.
